(57) **CLAIM**

The ornamental design for a glove with hook and loop fastener receivers, as shown and described.

DESCRIPTION

FIG. 1 shows a perspective view of a glove with hook and loop fastener receivers showing my new design;

FIG. 2 shows a front elevation view thereof;

FIG. 3 shows a back elevation view thereof;

FIG. 4 shows a left side elevation view thereof;

FIG. 5 shows a right side elevation view thereof;

FIG. 6 shows a top plan view thereof; and,

FIG. 7 shows a bottom plan view thereof.

The glove shown in evenly-incremented broken lines in the drawings is environmental structure and forms no part of the claimed design. The oval drawn in dot-dash-dot broken lines in FIG. 7 illustrates the bounds of the claimed design and forms no part thereof.
